RETRACTABLE BALL PEN

Blanchard D. Smith, Atlanta, Ga., assignor to Scripto, Inc., Atlanta, Ga., a corporation of Georgia

Application November 4, 1953, Serial No. 390,185

9 Claims. (Cl. 120—42.03)

This invention relates to ball point writing instruments, and in particular to writing instruments of this sort in which a ball point and reservoir unit is arranged for selective retraction within the instrument or pen barrel so that the ball point may be alternatively projected from the barrel for writing or retracted therein when not in use.

According to the present invention, the ball point and reservoir unit is arranged for projection and retraction alternately upon successive depressions of an operating plunger member slidably disposed at the rear end of the pen barrel, and a latching lever is rockably supported within the barrel and actuated from the plunger member so that it is rocked to a latching position with respect to the ball point and reservoir unit whenever this unit is moved forwardly to projected position, and is rocked oppositely to release the ball point and reservoir unit for retraction whenever the plunger member is depressed with this unit in projected position.

This arrangement and other features of the present invention are described in detail below in connection with the accompanying drawings, in which:

Fig. 1 is a vertical section of a retractable ball pen embodying the present invention, and in which the ball point and reservoir unit is shown in retracted position;

Fig. 2 is a vertical section corresponding to Fig. 1, but showing the plunger member and related elements depressed for projecting the ball point and reservoir unit;

Fig. 3 is a vertical section corresponding to Fig. 1 but showing the plunger member and related elements following recovery after projection of the ball point and reservoir unit;

Fig. 4 is an enlarged fragmentary detail of the top portion of the ball pen shown in Fig. 1, with the plunger member and pen barrel sectioned at right angles to Fig. 1, and with the remaining operating elements shown in full elevation;

Fig. 5 is a sectional detail taken substantially at the line 5—5 in Fig. 4;

Fig. 6 is a sectional detail taken substantially at the line 6—6 in Fig. 4;

Fig. 7 is a sectional detail taken substantially at the line 7—7 in Fig. 4;

Fig. 8 is a sectional detail taken substantially at the line 8—8 in Fig. 4; and

Fig. 9 is a sectional detail taken substantially at the line 9—9 in Fig. 4.

The embodiment of the present invention shown in the drawings comprises a ball point and reservoir unit as indicated generally by the reference numeral 10 that is retractably housed within a two-part barrel formed by a forward barrel portion 12 and a rear barrel portion 14. The forward barrel portion 12 forms the writing end of the pen and mainly houses the ball point and reservoir unit 10, this unit 10 consisting of a ball point element 16 fitted at the forward end of a tubular ink reservoir 18 that is yieldably biased rearwardly in the forward barrel portion 12, as by a spring 20, so as to maintain the ball point element 16 retracted within the forward barrel portion 12

2

as shown in Fig. 1, except when the unit 10 is latched at projected position.

The forward barrel portion 12 is reduced in diameter adjacent its rear end and is externally threaded at this 5 reduced rear end portion to engage a threaded sleeve 22 fitted within the forward end of the rear barrel portion 14 so as to provide for assembly of the two-part barrel as a unit. The rear barrel portion 14 is further formed with an inwardly extending annular flange 24 at its 10 rear end.

The previously mentioned operating plunger member, which is indicated in the drawings by the reference numeral 26, is slidably disposed at this rear barrel flange 24, the plunger member 26 being shouldered, as at 28, 15 to engage the flange 24 as an abutment limiting outward movement of the plunger member 26 with respect to the barrel. In order to guide the sliding movement of the plunger member 26 when it is depressed within the barrel, the forward plunger portion beyond its shoulder at 28 is 20 formed with external longitudinal grooves 30 at opposite sides, that are shaped to ride leg portions 32 extending rearwardly in the barrel portion 14 from a transverse plate portion 34 of a guide bracket 36 fixed in place intermediate the length of the rear barrel portion 14. This 25 guide bracket 36 is also apertured suitably to allow the rear end portion of the ink reservoir 18 to extend therethrough with a latching sleeve 38 disposed in covering relation, and to support a rocking latching lever 40.

The rear end portion of the ink reservoir 18 and the 30 latching sleeve 38 thereon are slidably received within the plunger member 26, which is recessed to provide a forwardly opening central bore 42 that terminates at a shoulder 44 beyond which a recessed bore 46 of smaller diameter continues to contain a plunger spring 48 in 35 opposed relation to an angled rear end portion 50 of an actuating or positioning lever 52 that is rockably interlocked with the latching sleeve 38 in the plunger member 26 and extends forwardly past a cam lip 54 and within a longitudinal slot 56 formed in the plunger member 26 40 below the cam lip 54 and forwardly of its shoulder 28, this longitudinal slot 56 extending for only a portion of the depth of the central plunger bore 42.

The above noted latching sleeve 38 is positioned on the 45 ink reservoir 18 by means of a transverse flange 58 formed from the sleeve wall to abut the rear end of the reservoir 18. This transverse flange 58 is spaced forwardly of but adjacent the rear end of the latching sleeve 38, and the latching sleeve 38 is longitudinally slotted as at 60 from its rear end adjacent the transverse flange 58. The longitudinal slot 60 extending from the rear of latching sleeve 38 terminates at latching sleeve guide lips 62, which are flared outwardly adjacent their forward edges, as at 62', for a purpose that will appear presently.

Beyond the guide lips 62, a second comparable longitudinal slot 64 continues forwardly in the latching sleeve 38 to terminate at forward notch lips 66 forming a rearwardly facing latching notch at the rear edges 66' thereof. Opposite the notch lips 66, the forward end of the latching sleeve 38 is notched at 68 in a width corresponding to that of the longitudinal slots 60 and 64 and in a length extending beyond the notch lips 66, so as to increase the lateral flexibility of the latching sleeve 38 at its forward end for easy insertion of the ink reservoir 18 therein.

When the ball point and reservoir unit 10 is in retracted position as shown in Fig. 1, the rear end of the latching sleeve 38 is bottomed in the central plunger bore 42 at the terminal shoulder 44 thereof, the opposed action of the annular barrel flange 24 containing the plunger member 26 within the rear barrel portion 14 and of the bias spring 20 yieldably urging the unit 10 rearwardly from the front barrel portion 12 resulting in

this bottomed disposition of the latching sleeve 38. Accordingly, the plunger member 26 when depressed will always act directly on the latching sleeve 38 to cause projection of the unit 10 when retracted.

The previously noted plunger spring 48, which extends from the smaller plunger bore 46 through the rear end portion of latching sleeve 38 to bear against the rear angled portion 50 of the positioning lever 52 is made weaker than the bias spring 20 so as not to interfere with retraction of the unit 10, and is provided for two purposes. First, the plunger spring 48 serves to bias the plunger member 26 rearwardly with respect to the latching sleeve 38 for recovery to normal position following a depression thereof to project and latch the unit 10 at projected position; and, secondly, the plunger spring 48 acts against the rear face of angled portion 50 to bias the forward end of the positioning lever 52 outwardly with respect to the latching sleeve 38 for operation to effect latching and unlatching of the unit 10.

The rockable internesting of the positioning lever 52 with the latching sleeve 38 is arranged by forming the rear lever portion 50 circularly in plan to fit and be contained rockably within the rear portion of the latching sleeve 38 above the transverse flange 58 with the remainder of the lever 52 disposed through the longitudinal latching sleeve slot 60 to extend forwardly in the plunger member 26 past the cam lip 54 and within the longitudinal plunger slot 56, as mentioned above. The transverse flange 58 of the latching sleeve 38 is spaced from the rear end thereof so that when the latching sleeve 38 is bottomed in the central plunger bore 42 this flange 58 is disposed rearwardly of the plunger cam lip 54 at a distance corresponding substantially to the extent of sliding movement of the unit 10, and of the latching sleeve 38 thereon, between retracted and projected positions (compare Figs. 1 and 3).

Consequently, when the unit 10 is in retracted position, the positioning lever 52 is withdrawn by the latching sleeve 38 within the central plunger bore 42 rearwardly of the cam lip 54 and thereby held inwardly against the latching sleeve guide lips 62, which are disposed rearwardly adjacent the forward end of the positioning lever 52 at a spacing less than the spacing of transverse flange 58 from the rear end of latching sleeve 38 but greater than the extent by which downward movement of the plunger member 26 is allowed in excess of the distance between retracted and projected positions of the unit 10, as noted further below, as seen in Figs. 1 and 2; although when the unit 10 is latched in projected position and the plunger member 26 has recovered under the bias of the plunger spring 48, as seen in Fig. 3, the positioning lever 52 is disposed within the longitudinal plunger slot 56 free of restraint by the cam lip 54 so that it is rocked outwardly from the latching sleeve 38 by the plunger spring 48 in preparation for unlatching the projected unit 10 in order to release the unit 10 for return to retracted position under the force of the bias spring 20, when desired.

Latching of the unit 10 in projected position is accomplished by means of the previously mentioned latching lever 40 which is rockably supported in the rear barrel portion 14 adjacent the latching sleeve 38 by the plate portion 34 of guide bracket 36 to engage the rearwardly facing edges 66' of the latching sleeve notch lips 66 when the unit 10 and latching sleeve 38 are projected. The plate portion 34 of the guide bracket 36 is fixed transversely in the rear barrel portion 14 at a position intermediate of the length of the latching sleeve 38 and beyond the forward extent of the positioning lever 52.

The latching lever 40 is formed for rockable support on the guide bracket plate portion 34 (as shown best in Fig. 4) with a relatively narrow intermediate shank 70 at which it is adapted to extend through the apertured form of the guide bracket plate portion 34, a widened forward portion 72 that is arranged for abutting relation with the bottom face of the guide bracket plate portion 34

and that tapers to a transversely rounded forward end 74 provided to engage the rearwardly facing edges 66' of the latching sleeve notch lips 66; and a rearward wing portion 76 having a pair of spaced lateral lugs 78 formed inwardly at the bottom edge thereof to rest rockably on the top face of the guide bracket plate portion 34 and a lateral lip 80 formed outwardly for cooperation with the forwardly extending end of the positioning lever 52.

The proportions of the latching lever 40 are such that, with the unit 10 in retracted position, the rounded forward end 74 extends forwardly of the rear edges 66' of latching sleeve notch lips 66 a distance equal to the distance between retracted and projected positions of the unit 10, and the rear lateral lip 80 is disposed below the outwardly flared forward edges 62' of the latching sleeve guide lips 62 at a spacing slightly in excess of this distance so as to provide overtravel clearance for allowing the latching lever forward end 74 to move easily in behind the rear notch lip edges 66' for latching engagement therewith upon projection of the unit 10 and the latching sleeve 38 thereon, the latching lever 40 having a suitably arranged profile, as shown, for disposition on the guide bracket plate portion 34 to rock between a latching position and a free position with respect to latching sleeve 38.

The operation of the above described retractable ball pen mechanism of the present invention is as follows. Starting with the unit 10 in retracted position as shown in Fig. 1, depression of the plunger member 26 results directly in moving the unit 10 forwardly toward projected position by reason of the bottomed disposition of latching sleeve 38 in the central plunger bore 42. At the same time, the positioning lever 52 is carried forward with the latching sleeve 38 and held inwardly at its forward end against the latching sleeve guide lips 62 so as to be in position for endwise abutment with the latching lever lateral lip 80.

When this abutment is established, the plunger spring 48 yields to allow continued forward movement of the latching sleeve 38 with the unit 10, while the positioning lever 52 remains stationary in abutment with the latching lever lateral lip 80 and maintains pressure thereon from the plunger spring 48. Forward movement of the latching sleeve 38 and unit 10 continues until the outwardly flared forward edges 62' of the latching sleeve guide lips 62 also reach abutting relation with the latching lever lateral lip 80, as seen in Fig. 2.

The guide lips 62 are outwardly flared at 62' to facilitate establishment of this abutting relation, which limits the plunger member 26 against further downward movement. Also, the outwardly flared guide lip forward edges 62' function to cam outwardly the forward end of positioning lever 52 (which may be angled inwardly adjacent its forward end, as at 52', for the same purpose) with respect to the latching lever lateral lip 80, and thereby further accentuate the pressure thereon from the positioning lever 52 and plunger spring 48.

As the downward movement of the plunger member 26 is limited by the guide lip edges 62' at a distance slightly in excess of the distance to projected position of the unit 10, the rear notch lip edges 66' of latching sleeve 38 will now have been moved downwardly past the forward end 74 of latching lever 40 allowing lever 40 to rock to latching position by reason of the pressure thereon, and the forward latching lever end 74 will accordingly be disposed behind the rear notch lip edges 66' for latching engagement therewith to hold the latching sleeve 38 and unit 10 in projected position upon release of plunger member 26, as seen in Fig. 3.

The plunger member 26 is caused to recover its original position, upon release at this time, by the plunger spring 48; and, as this recovery takes place, the plunger spring 48 also holds the positioning lever 52 forwardly toward the transverse latching sleeve flange 58 and rocks the forward end of lever 52 outwardly within the longitudinal plunger slot 56 as it is released by the plunger

cam lip 54. This outward rocking of the positioning lever 52 under the pressure of plunger spring 48 results in moving its forward end off of the rear face of the latching lever lateral lip 80 to extend at the side thereof for lateral abutment with the outwardly extending edge of latching lever lateral lip 80.

Accordingly, upon the next succeeding depression of plunger member 26, the plunger cam lip 54 will function to press or rock the positioning lever 52 inwardly in such lateral abutment and thereby cause rocking of the latching lever 40 to its free position so as to unlatch the latching sleeve 38 and allow it to return with the unit 10 to retracted position under the force of bias spring 20, so that all of the operating elements will again resume their original Fig. 1 disposition.

The present invention has been described above for purposes of illustration only and is not intended to be limited by this description or otherwise except as defined in the appended claims.

I claim:

1. A retractable ball pen comprising a barrel, a ball point and reservoir unit housed within said barrel for sliding movement between forward projected and rearward retracted positions with respect thereto and yieldably biased therein rearwardly toward said retracted position, a latching sleeve disposed over the rear portion of the reservoir of said unit for sliding movement therewith and having a transverse flange abutting the rear end of said reservoir, said transverse flange being spaced forward of but adjacent the rear end of said latching sleeve and the rear latching sleeve portion adjacent said transverse flange being longitudinally slotted, a plunger member slidably contained at the rear end of said barrel and projecting rearwardly therefrom, said plunger member having a forwardly opening central bore in which the rear end of said latching sleeve is slidably received, said plunger member being longitudinally slotted from its forward end for a portion of the length of said bore, a positioning lever having an angled rear portion rockably internested within said latching sleeve at the rear portion thereof beyond said transverse flange, said positioning lever extending forwardly through the longitudinal slot of said latching sleeve and within the longitudinal slot of said plunger member, yieldable means contained in the central bore of said plunger member biasing said plunger member rearwardly and extending forwardly within said rear latching sleeve portion to bear on the rear angled portion of said positioning lever, and a latching lever rockably supported intermediate its length in said barrel adjacent said latching sleeve for rocking between a latching position and a free position with respect to said latching sleeve, said latching lever having a lateral lip thereon at its rearward end, the forward end of said positioning lever engaging said lateral lip endwise for rocking said latching lever to said latching position in engagement with said latching sleeve and engaging said lateral lip laterally for rocking said latching lever to said free position in disengagement with said latching sleeve, said endwise and lateral engagements occurring upon successive depressions of said plunger member.

2. A retractable ball pen as defined in claim 1 and further characterized in that said latching lever is rockably supported in said barrel by a guide bracket fixed within said barrel, said latching lever having a pair of spaced lateral lugs formed thereon in spaced relation to said lateral lip and at the extending ends of which lateral lugs said latching lever is rockably supported on said guide bracket.

3. A retractable ball pen as defined in claim 2 and further characterized in that said lateral lip is arranged at the rear end of said latching lever and said lateral lugs are arranged intermediately of the length thereof, 75

and said lateral lip extends outwardly and said lateral lugs inwardly with respect to said latching sleeve.

4. A retractable ball pen as defined in claim 1 and further characterized in that a guide bracket is fixed within said barrel for rockably supporting said latching lever and for guiding the sliding movement of said ball point and reservoir unit together with the latching sleeve thereon and said plunger member, said guide bracket having a plate portion disposed transversely of said barrel at a position intermediate of the length of said latching sleeve and beyond the forward extent of said positioning lever, said plate portion being apertured for slidably aligning said latching sleeve and for supporting engagement with said latching lever, said guide bracket being further formed with leg portions extending rearwardly from said plate portion, and said plunger member being formed with external longitudinal grooves shaped to ride said leg portions.

5. A retractable ball pen as defined in claim 4 and further characterized in that said latching lever is engaged intermediate its length for rockable support by said guide bracket, and said latching sleeve is formed with a rearwardly facing latching sleeve notch adjacent the forward end thereof, the forwardly extending end of said latching lever being engageable at said latching position, with said latching sleeve notch only when said latching sleeve and unit are moved to projected position.

6. A retractable ball pen comprising a barrel, a ball point and reservoir unit housed within said barrel for sliding movement between forward projected and rearward retracted positions with respect thereto and yieldably biased therein rearwardly toward said retracted position, a plunger member slidably contained at the rear end of said barrel and projecting rearwardly therefrom, said plunger member having a forwardly opening central bore recessed therein and being longitudinally slotted from the forward end thereof for a portion of the depth of said central bore and terminating at an inwardly facing cam lip, a latching sleeve disposed over the rear end portion of the reservoir of said unit and extending slidably within the central bore of said plunger member, said latching sleeve being formed with a transverse flange spaced adjacent the rear end thereof abutting the rear end of said unit reservoir, the rear end of said latching sleeve being bottomed in said central plunger bore by the yieldable bias on said unit when retracted, said latching sleeve being further formed with a first longitudinal slot extending from the rear end thereof past said transverse flange and guide lips arranged intermediate the length of said latching sleeve and terminating said first slot, said latching sleeve having a second longitudinal slot separated from said first slot by said guide lips and continuing forwardly from said guide lips, notch lips arranged at the forward end of said latching sleeve and terminating said second slot, a positioning lever having an angled rear portion rockably contained within said latching sleeve rearwardly of said transverse flange with the remaining portion of said positioning lever extending forwardly through the first longitudinal slot of said latching sleeve past said plunger cam lip and within said plunger longitudinal slot, a spring contained within said central plunger bore and extending forwardly in said latching sleeve against the rear angled portion of said positioning lever, said spring exerting a weaker bias than the yieldable rearward bias on said unit, and a latching lever rockably supported in said barrel for rocking of the forward end thereof between a latching position in abutment with the rear edges of said latching sleeve notch lips and a position free thereof, the rear end of said latching lever having a lateral lip thereon

disposed for limiting abutment with the forward edges of said latching sleeve notch lips and for alternative engagement endwise or laterally by the forward end of said positioning lever to effect rocking of said latching

lever from one of the latching and free positions thereof to the other upon successive depressions of said plunger member, the forward end of said latching lever extending forwardly of the rear edges of said latching sleeve notch lips in a length equal to the distance between retracted and projected positions of said ball point and reservoir unit and said latching sleeve thereon, the lateral lip at the rear end of said latching lever being disposed below the forward edges of said latching sleeve guide lips at a spacing slightly in excess of said distance, the forward end of said positioning lever extending forwardly of the forward edges of said latching sleeve guide lips in a length greater than the extent by which said lateral lip spacing exceeds said distance but less than the spacing of said transverse flange from the rear end of said latching sleeve, and said transverse flange being spaced on said latching sleeve so that when said sleeve is bottomed in said central plunger bore said flange is disposed rearwardly of said plunger cam lip at a spacing substantially equal to said distance.

7. A retractable ball pen comprising a barrel, a ball point and reservoir unit housed within said barrel for sliding movement between forward projected and rearward retracted positions with respect thereto and yieldably biased therein rearwardly toward said retracted position, a latching sleeve disposed over the rear end of the reservoir portion of said unit and having a rearwardly facing latching notch therein, a latching lever rockably supported in said barrel for rocking between a latching position and a free position with respect to said latching sleeve, said latching lever extending forwardly in said barrel and engageable at said latching position with said latching sleeve notch when said latching sleeve and unit are moved to projected position, a 35 plunger member slidably contained at the rear end of said barrel and compressible within said barrel for operating directly to project said latching sleeve and unit to said latching position, yieldable means arranged within said plunger member and biasing said plunger member rearwardly, and a positioning lever rockably actuated by depression of said plunger member for engaging and rocking said latching lever to said latching position in engagement with said latching sleeve notch upon projection of said latching sleeve and unit by depression of said plunger member and for engaging and rocking said latching lever to said free position upon a subsequent depression of said plunger member.

8. A retractable ball pen comprising a barrel, a ball point and reservoir unit housed within said barrel for 50

sliding movement between forward projected and rearward retracted positions with respect thereto and yieldably biased therein rearwardly toward said retracted position, a latching sleeve disposed over the rear end of the reservoir portion of said unit for sliding movement therewith, a plunger member slidably contained at the rear end of said barrel, said plunger member having a forwardly opening central bore in which the rear end of said latching sleeve is slidably received, yieldable means arranged within said central bore and biasing said plunger member rearwardly, a guide bracket fixed in said barrel adjacent the rear end thereof for aligning the sliding movement of said latching sleeve and unit and of said plunger member within said barrel, a latching lever rockably supported intermediate its length by said guide bracket in said barrel for rocking between a latching position and a free position with respect to said latching sleeve, said latching sleeve being formed with a rearwardly facing latching sleeve notch adjacent the forward end thereof, the forwardly extending end of said latching lever being engageable at said latching position with said latching sleeve notch when said latching sleeve and unit are moved to projected position, said latching lever having a lateral lip thereon at its rearward end, a positioning lever engaging said lateral lip endwise for rocking said latching lever to said latching position in engagement with said latching sleeve notch, and engaging said lateral lip laterally for rocking said latching lever to said free position in disengagement with said latching sleeve notch, said endwise and lateral engagements occurring upon successive depressions of said plunger member.

9. A retractable ball pen as defined in claim 8 and further characterized in that said guide bracket has a plate portion disposed transversely of said barrel at a position intermediate the length of said latching sleeve and beyond the forward extent of said positioning lever, said plate portion being apertured for slidably aligning said latching sleeve and for supporting engagement with said latching lever.
